(57) **CLAIM**

The ornamental design for an aeroponic plant growing system as shown and described.

DESCRIPTION

FIG. 1 is a front elevation view of an aeroponic plant growing system; the rear elevation view thereof is identical to FIG. 1;

FIG. 2 is a top plan view thereof;

FIG. 3 is a left side elevation view thereof; the right side elevation view thereof is identical to FIG. 3; and,

FIG. 4 is a bottom plan view thereof.
